[57] CLAIM

The ornamental design for a distance measuring ski attachment, as shown and described.

DESCRIPTION

FIG. 1 is a front and top-right perspective view of a distance measuring ski attachment showing my new design;

FIG. 2 is a left side elevational view thereof;

FIG. 3 is a top plan view of FIG. 2;

FIG. 4 is a bottom plan view of FIG. 2;

FIG. 5 is a front elevational view thereof;

FIG. 6 is a rear elevational view thereof;

FIG. 7 is a left side elevational view thereof with the movable arm in an extended position.

FIG. 1

FIG. 2

FIG. 3

FIG. 4

FIG. 5

FIG. 6

FIG. 7
